UNITED STATES PATENT OFFICE.

CLIFFORD C. CARPENTER, OF WHITE PLAINS, NEW YORK.

RAIN CATCHER.

Application filed August 18, 1926. Serial No. 129,996.

This invention relates to rain catchers.

An object of the invention is to provide a device which may be placed outdoors and which when not desired for use may be closed so as to exclude dust, dirt and foreign particles, and when it is desired to catch the rain may be opened and the interior thereof will be clean so that the water will not be dirty nor contaminated.

10 A further object is to provide a device of this character which is comparatively simple in construction, cheap to manufacture and hence efficient in performance of its functions.

15 With these and other objects in view, the invention consists in certain novel features of construction and combinations and arrangements of parts, which will be more fully hereinafter described and pointed out in the claims.

In the accompanying drawings—

Figure 1 is a top plan view, showing my improved device in open position ready to catch the rain;

25 Figure 2 is a view in side elevation of Figure 1;

Figure 3 is a view in transverse section on the line 3—3 of Figure 1.

1 1 represents a receptacle which may be of any size and shape and which is supported upon a frame 2. This support and the frame are preferably of metal, although of course I do not limit myself to the particular materials employed.

35 3 represents a second receptacle which is slightly larger than the receptacle 1 and is connected to the receptacle 1 by a hinge 4 so that the receptacle 3 may be swung to position over the receptacle 1 and function as a cover, as indicated in dot and dash lines in Figure 2. When the receptacle 3 is over the receptacle 1 it will telescope on the latter a sufficient distance and fit with such snugness as to exclude dirt and dust from the interior of the receptacle.

5 5 represents a brace arm or extension fixed to the frame 2 and projecting outwardly therefrom so as function as a support for the receptacle 3, as shown in full lines in Figure 2. This arm 5 at its extremity has

a finger 6 thereon adapted to receive a ring 7 on the receptacle 3 and holds the latter against the possibility of accidental displacement.

The receptacle 1 has a drain outlet 8 and the receptacle 3 has a drain outlet 9. These outlets 8 and 9 are located, although not necessarily, in adjacent corners of the receptacles.

10 10 represents a drain pipe communicating with the outlet 8 and extending to any point of discharge. This outlet pipe 10 has a nipple 11 thereon which is connected by a flexible hose 12 with nipple 13 communicating with drain outlet 9. This hose 12 is of sufficient length and flexibility to allow the receptacle or cover 3 to be removed from one position to another and when the device is in operative position functions to carry the water from the receptacle 3 into drain 70 pipe 10.

15 It will be noted, particularly by reference to Figures 2 and 3, that the bottoms of the receptacles 1 and 3 have an inclination or taper in a direction toward the drain outlets 75 so that such rain as falls within the receptacles will drain freely therefrom.

20 Various changes and alterations might be made in the general form of the parts described without departing from the spirit 80 of my invention, and hence I do not limit myself to the precise details set forth but consider myself at liberty to make such slight changes and alterations as fairly fall within the spirit and scope of the appended 85 claims.

I claim:

1. A device of the character described, including two receptacles adapted to be positioned one over the other when closed, and means connected to the receptacles for draining rain therefrom.

2. A device of the character described, including a support, a receptacle on the support, a second receptacle hingedly connected to the first-mentioned receptacle, a fixed drain connected to one receptacle, and a flexible drain connecting the other receptacle with the first-mentioned drain.

3. An apparatus of the character de- 100

scribed, including a support, a fixed arm on the support, a receptacle secured to the support, a second receptacle connected to the first-mentioned receptacle and adapted when open to rest upon the arm, a finger on the arm, a ring on the last-mentioned receptacle adapted to engage over the arm, said recep-

tacles having outlet drains at their low points, a drain pipe communicating with one of said outlets, and a flexible pipe connecting the first-mentioned pipe with the other of said outlets. ¹⁰

CLIFFORD C. CARPENTER.
